ANDREW JOHNSON AND WALTER H. ELLIOTT, OF BLOOMINGTON, ILLINOIS.

Letters Patent No. 64,770, dated May 14, 1867.

IMPROVEMENT IN MOTIVE POWER.

The Schedule referred to in these Letters Patent and making part of the same.

TO ALL WHOM IT MAY CONCERN:

Be it known that we, ANDREW JOHNSON and W. H. ELLIOTT, of Bloomington, in the county of McLean, and State of Illinois, have invented a new and improved Motive Power; and we do hereby declare that the following is a full, clear, and exact description thereof, reference being had to the accompanying drawings, making a part of this specification, in which—

Figure 1 is a plan view of the motive power.

Figure 2 is a vertical section through the apparatus, taken in the course indicated by red line $z z$.

Figure 3 is a longitudinal section, taken in the vertical plane indicated by red line $y y$ in fig. 2.

Figures 4 and 5 show side sections of the ported hub.

Similar letters of reference indicate corresponding parts in the several figures.

This invention relates to a new and improved motive power, which is designed for driving all kinds of machinery. It consists in the application to a wheel, which is partly submerged in water or other liquid, of air-tight expandible bags or buoys, which are applied near the circumference of this wheel, and communicate, through its ported hub, with bellows or other air-pumps, and also with the open air, all being so arranged that, upon forcing air into those buoys which are beneath the surface of the water, and at the same time allowing the air to escape from those buoys which are out of the water, the wheel will be caused to rotate by the successive ascension of the submerged buoys, as will be hereinafter described.

The following description will illustrate one practical mode of carrying our invention into effect.

In the accompanying drawings, A represents a rectangular vessel, which is adapted for containing the mechanical movement which we are about to describe. This vessel is divided into two apartments by a partition, A', and the apartment B is adapted for containing water or other liquid. C represents a wheel, which is secured to a horizontal shaft, D, so as to rotate freely within the chamber B. This wheel is constructed with a hub, a, having a number of ports, b, through it, which ports are arranged concentrically and at regular distances apart around the axis of the wheel, as shown in fig. 2. Twelve ports b are represented through said hub a. From this hub project twelve hollow spokes c, which communicate at their inner ends with the ports b, and at their outer ends with bags or buoys d. These bags or buoys d may be made of any flexible substance which is impervious to air; they should be secured air-tight to the spokes, and may enclose the ends thereof. On that side of the hub a nearest to the partition A', and rigidly secured to this partition, is a hub, e, which receives through its centre the shaft D, and which forms an inner bearing for the latter. On the opposite end of the hub a, and rigidly secured to the side of the vessel A, is a corresponding hub-section, e', which receives the outer end of the shaft D through its axis, and forms a bearing therefor. The two hub-sections e e' are applied to the ends of the turning hub a in the manner shown in fig. 3, or in any other suitable manner which will prevent the escape of air between the abutting surfaces and allow the wheel C to rotate freely. The section e has a port, f, through it, communicating with a segment-groove, f', upon the inner face of this section, as shown in fig. 4. This port f is in a vertical plane intersecting the axis of the shaft D, and is the induction port for forcing air into three of the ports b b b and bags or buoys d at one and the same time. The air is supplied under pressure from two bellows E E, which communicate with the part f through hub e by means of the horizontal pipe or conduit F, shown in figs. 1 and 3. These bellows are double-acting, and are supported by means of standards G G, which carry, near their upper ends, horizontal rock-shafts g g, to which are pivoted the working-beams or levers H H. The hub-section e' has six ports h through it, as shown in fig. 5, which, at certain times, form communications between the ports b through the hub a and the open air. These exhaust-ports h are so arranged with relation to the position of the ports b, whose buoys are out of the water, that, as soon as the buoys rise out of the water the air is allowed to escape from them, so that they descend into the water empty. The shaft D carries on one end a wheel, D', to the surface of which a pitman-rod, I, is attached, the lower end of which is pivoted to an arm, J, projecting from a horizontal rock-shaft, J', below the pipe F. The shortest arms of levers H H are connected, by means of rods i i, to the bellows E E, and the longest arms of these levers H are connected to arms K K, projecting from rock-shaft J' by means of pitman-rods L L.

It will be seen that when the wheel C is rotated the bellows will be operated, and air will be forced into those bags or buoys of wheel C which are in communication with the port f and passage f'. Upon filling three of the expandible bags or buoys which are below the surface of the water with air, they will rise and

carry down into the places occupied by them three empty buoys, which in their turn will be filled with air, and caused to rise out of the water, thus carrying down three more buoys to be filled with air, and so on the buoys are successfully submerged and filled with air, and caused to ascend by their superior buoyancy. As the filled buoys pass the exhaust ports through section e' , the air escapes from them, so as to allow them to be carried down into the water with comparatively little resistance.

Having described one mode of carrying out our invention, we do not desire to confine ourselves to the precise form and arrangement of parts specified, as these may be varied in many ways without changing the principle of the invention.

Having described our invention, what we claim as new, and desire to secure by Letters Patent, is—

The motive power which is constructed and operated substantially as herein described.

ANDREW JOHNSON,
WALTER H. ELLIOTT.
